UNITED STATES PATENT OFFICE.

FREDERICK M. WEISS, OF CHICAGO, ILLINOIS, ASSIGNOR TO NYE COMPANY, A CORPORATION OF ILLINOIS.

DETACHABLE-BLADE KNIFE.

Application filed February 25, 1927. Serial No. 170,979.

This invention relates to improvements in detachable blade knives, and more particularly to a device of that character in which the blade is made of thin sheet-metal, which is more or less flexible; so that the handle, in which the blade is mounted for use, not only holds the blade, but also reinforces and stiffens it to a certain extent.

This invention embodies more particularly an improvement over the knife shown in Brix Patent No. 1,458,104 of June 5, 1923. The general operation and construction of the knife is the same as shown in that patent; and I shall describe and point out in detail 15 the improvement in the present invention.

The invention will be fully understood by reference to the following specification and accompanying drawing, in which Figure 1 is a view in side elevation of a device embodying the features of my invention, Figure 2 is a top plan view, Figure 3 is a view on an enlarged scale showing one of the blades removed from the handle, Figure 4 is a vertical sectional view of the handle taken 25 on line 4—4 of Fig. 2, Figure 5 is a view similar to Fig. 4 showing the blade in place, and Figure 6 is a view taken as indicated by the line 6 of Fig. 4.

As shown in the drawings, the handle of 30 the knife comprises a hand-grip portion 10, having at one end a blade-supporting portion comprising two parallel prongs 11, separated by a slot 12 with parallel sides. The two prongs 11 are joined near their ends 35 by a pin 13, which extends across the slot 12.

Mounted in the part 10 of the handle at the end where the prongs 11 join, is a circular spring 17 as shown. This spring is put in place by snapping the same in a suitable 40 pocket formed in the handle as shown and is held against rotation by the pin 17.

In Fig. 3 is shown one of the blades 50. This blade is made preferably of thin sheet-metal. Blades from such metal can be easily 45 and cheaply made; and can ordinarily be stamped out in the shape shown. Such metal is usually more or less flexible. 20 indicates the cutting edge of the blade. The upper edge 21 of the blade is provided with a downwardly and rearwardly extending notch or cut 22 with substantially parallel edges, adapted to accommodate the pin 13, when the blade is in place. The back end 50

of the blade is convexly curved, as indicated by 23. In this curve and at about the center, is provided a recess or notch 24. The bottom of the rear edge of the blade is also provided with a depending tongue 26. The forward end of the part 10 of the handle, where it meets the rear end of the slot 12, is concavely curved, as indicated by 30, to correspond with the convex curve 23 on the rear end of the blade. The spring 17 is so located that it projects slightly into the slot 12, as shown. 55 60 65

In operation, the blade 50 is placed in the slot 12 behind the pin 13, and moved so that the cut or slot 22 embraces the pin 13; so that it will be in position, as indicated by the broken lines in Fig. 5. The back 70 end of the blade is then pressed downwardly, causing the blade to rotate on the pin 13, until the notch 24 at the rear of the blade snaps over the spring 17. When in this position the convexly curved rear end 75 23 of the blade will be a slight distance in front of the concavely curved forward edge 30 of the handle. That is, the recess or notch 24 of the blade will be rested against the spring 17. The parts are shown in this 80 position in solid lines in Fig. 5 where the space between the edge 23 of the blade and the edge 30 of the handle is indicated by 75. It will be seen that when in this position, that the blade could be pressed rearwardly against the spring 17 to close the space 75 unless means are provided to prevent such rearwardly sliding of the blade. 85

That is, the blade would have a certain amount of forward and backward sliding 90 movement unless prevented by suitable means. One of the features of this invention is to provide such means to prevent such sliding movement of the blade as a distinct improvement over the blade shown in the 95 Brix Patent No. 1,458,104, above referred to. To prevent this movement above referred to, I provide in the blade 50 near the rear end another slot 76 that is substantially vertical and has substantially parallel edges. A 100 slight curvature, however, is given to this slot. There is also provided between the prongs 11 another pin 77 near the rear end adapted to be embraced by the slot 76 as the blade is moved into place. This is shown in 105 Fig. 5. When the pin 77 is thus embraced

by the slot 76 it will be seen that backward movement of the blade in the device is prevented and consequently the blade is held firmly in position for use.

5 The slot 76 has its sides, near the points of contact with the pin, substantially at right angles with a line connecting the two pins 13 and 77 when the blade is in position. This slot also is narrow enough so that it 10 snugly embraces the pin 77. This relationship definitely prevents a longitudinal sliding movement of the blade after it is in position.

In removing the blade, upward pressure 15 on the tongue 26 will release the notch 24 from the spring 17, permitting the back end of the blade to be sprung upwardly, to swing the notch 76 clear of the pin 77, until the rear end of the blade is substantially in the position shown by the broken lines in Fig. 5. The notch or cut 22 can then be removed 20 from the pin 13 and the blade lifted out.

It will be noted that the prongs 11 of the handle are considerably thicker than the 25 blade and extend forwardly more than half of the length of the blade. These prongs not only assist in supporting the blade in the handle, but also strengthen and stiffen it and prevent bending of the blade in use.

30 While I have shown and described certain embodiments of my invention, it is to be understood that it is capable of many modifications. Changes therefore in the construction and arrangement may be made without 35 departing from the spirit and scope of the invention as disclosed in the appended claims, in which it is my intention to claim all novelty inherent in my invention as broadly as possible in view of the prior art.

40 What I claim as new and desire to secure by Letters Patent, is:

1. In a device of the character described, a handle comprising a hand-grip portion and a blade-supporting portion, the blade-supporting portion comprising two parallelly arranged stiff prongs with a slot between 45 adapted to accommodate a thin flexible blade, a pin joining the prongs near their forward ends, a thin flexible blade adapted to fit in the slot between the prongs, a notch in the upper edge of the blade adapted to embrace the pin joining the ends of the prongs, a notch at the back end of the blade adapted to engage with spring means in the handle, 50 a second pin joining the prongs near their rear ends, and a notch in the lower edge of the blade adapted to snugly embrace said pin as the blade is put into position.

60 2. A thin flexible blade provided with a downwardly and rearwardly extending slot with parallel sides at its upper edge, and an upwardly extending slot at its lower edge,

and having its back end convexly curved and provided with a notch.

3. In a device of the character described, 65 a handle comprising a hand-grip portion and a blade-supporting portion, the blade-supporting portion comprising two parallelly arranged stiff prongs with a slot between 70 adapted to accommodate a thin flexible blade, a pin joining the prongs near their ends, a thin flexible blade adapted to fit in the slot between the prongs and provided at its upper edge with a downwardly and rearwardly extending notch adapted to embrace 75 said pin, means for yieldingly pressing the blade forward to retain the pin in the notch, and means to prevent backward sliding movement of the blade against said forward 80 pressing means after the blade is in position.

4. In a device of the character described, 85 a handle comprising a hand-grip portion and a blade-supporting portion, the blade-supporting portion comprising two parallelly arranged stiff prongs with a slot between 90 adapted to accommodate a thin flexible blade, a pin joining the prongs near their ends, a thin flexible blade adapted to fit in the slot between the prongs and provided at its upper edge with a downwardly and rearwardly extending notch adapted to embrace 95 said pin, means for yieldingly pressing the blade forward to retain the pin in the notch, and means to prevent backward sliding 100 movement of the blade against said forward pressing means after the blade is in position, said means comprising a pin between the prongs and a notch in the blade, said pin adapted to be snugly embraced by said notch as the blade is put into position.

5. In a device of the character described, 105 a handle comprising a hand-grip portion and a blade-supporting portion, the blade-supporting portion comprising two parallelly arranged stiff prongs with a slot between 110 adapted to accommodate a thin flexible blade, a pin joining the prongs near their ends, a thin flexible blade adapted to fit in the slot between the prongs and provided at its upper 115 edge with a downwardly and rearwardly extending notch adapted to embrace said pin, a notch at the back end of the blade adapted to engage with spring means in the handle, and means to prevent backward movement 120 of the blade against said spring means after the blade is in position, said means comprising a pin between the prongs and a notch in the blade, said pin adapted to be snugly embraced by said notch as the blade is put into position.

In witness whereof, I have hereunto set my hand this 21 day of February, A. D. 1927.

FREDERICK M. WEISS.
